APPARATUS FOR FORMING AND DIMPLING ANGULAR BENDS IN RECTANGULAR TUBING

Francis J. Fuchs, Jr., and Ralph C. Taylor, Winston-Salem, N.C., assignors to Western Electric Company, Incorporated, New York, N.Y., a corporation of New York

Application February 26, 1954, Serial No. 414,030

1 Claim. (Cl. 153—3)

This invention relates broadly to apparatus for forming tubing, and more particularly to improved apparatus for simultaneously forming and dimpling angular bends in rectangular tubing.

It is frequently necessary in the fabrication of electrical assemblies utilizing wave guide tubing to effect angular bends in the wave guide tubing. It is desirable to maintain the interior dimensions of the tube uniform to prevent undesirable alteration of the electrical transmission characteristics of the tubing.

A first step in forming angular bends in such tubing comprises bending the tubing into a smooth, curvilinear form. A second step comprises inserting the curved tubing from the first step into a suitable die and performing a forming operation upon the tube to produce the final desired angular configuration.

It is also frequently required to alter the electrical transmission characteristics of wave guide tubing in a predetermined fashion such as, for example, producing concavo-convex dimples or corrugations in the tube. In the past the production of such predetermined deformations of the wave guide tubing has been done in a separate step subsequent to the forming of the tubing.

Such forming and dimpling procedures and apparatus therefor are disclosed in co-pending application of Francis J. Fuchs, Jr., Serial Number 305,325, and now Patent No. 2,835,306, filed August 20, 1952.

It is an object of the present invention to provide an improved apparatus for operating upon a curvilinear section of rectangular tubing to produce an angular bend therein.

It is also an object of this invention to provide a tube forming apparatus whereby deformations of an accurately controlled character may be produced in a tube substantially simultaneously with the forming of the tube to an angular configuration.

Another object of the present invention is to provide an improved apparatus for maintaining the interior cross-section of a tube substantially uniform while the exterior of the tube is subjected to a forming operation.

In accordance with the above objects one embodiment of the present invention provides a tube forming apparatus including a base having a plurality of stationary die sections rigidly mounted thereon and forming therebetween a die cavity for the reception therein of a tube to be formed. A movable die section is reciprocably mounted upon the base and is provided with a plane forming surface having convex dimpling projections or punches thereon for angularly forming and simultaneously producing concavo-convex dimples in one wall of the tube. An operating head is reciprocably mounted upon the base and has attached thereto a convex forming die for producing an angular configuration in another wall of the tube. A four-piece sectional mandrel is slidably insertable within the tube and is provided with a plurality of concavities complementary in location and configuration to the convex projections on the

2

movable die section. Means are provided to actuate the operating head and the movable die section whereby the tube assumes an angular configuration and is also dimpled by being formed between the convex projections of the movable die section and the concavities of the sectional mandrel. A top plate is provided for attachment to the stationary die sections in order to hold the tube in place during the forming operation.

A second embodiment of the present invention provides an apparatus for performing an operation similar to that performed by the first embodiment and includes a base having a plurality of stationary die sections rigidly mounted thereon and forming therebetween an angular die cavity for the reception therein of a tube to be formed. 10 A movable die section is reciprocably mounted upon the base and is provided with a plane surface having a plurality of convex projections extending therefrom. An operating head is reciprocably mounted upon the base and has a convex forming die rigidly secured thereto. 15 A movable die section is reciprocably mounted upon the base and is provided with a plane surface having a plurality of convex projections extending therefrom. An operating head is reciprocably mounted upon the base and has a convex forming die rigidly secured thereto. 20 Two side-engaging mandrels are slidably insertable within the tubing and are provided at first extremities thereof with grooves and slidable sections mounted in the grooves. The mandrels and the slidable sections are provided with arcuate surfaces defining concavities corresponding to 25 the location and configuration of the dimples which it is desired to produce in the tube. The slidable sections are adapted to move in the grooves relative to the mandrels to allow the mandrels to be withdrawn from the dimpled tube. Means are provided for actuating the operating 30 head and the movable die section into engagement with the tube to form and dimple the tube.

Other novel features and advantages of the present invention will become apparent from an inspection of the following description when considered in conjunction 35 with the accompanying drawings wherein:

Fig. 1 is a top plan view of the first embodiment of the invention showing a tube in place within the die cavity and the mandrel assembled within the tube prior to the actuation of the apparatus, the upper portion of 40 the tube being removed for clarity;

Fig. 2 is a view similar to Fig. 1 after the actuation of the apparatus;

Fig. 3 is a perspective view of the top plate of the first embodiment of the invention;

Fig. 4 is a cross-sectional view taken on line 4—4 of 45 Fig. 2, but with the top plate in position;

Fig. 5 is a perspective view of a tube prior to the forming operation by the first embodiment;

Fig. 6 is a perspective view showing the tube after the 50 forming thereof with the sectional mandrel partially retracted from the tube;

Fig. 7 is a top plan view of the second embodiment of the invention showing a tube in place in the die cavity prior to the actuation of the apparatus, but with the upper portion of the tube removed;

Fig. 8 is a view similar to Fig. 7 after the actuation of 55 the apparatus;

Fig. 9 is a fragmental top plan view of a portion of the mandrel showing the slidable section in position;

Fig. 10 is a cross-sectional view taken on line 10—10 of Fig. 9;

Fig. 11 is a perspective view of the tube prior to the forming and dimpling operations by the second embodiment, and

Fig. 12 is a perspective view of the tube after the forming and dimpling operations by the second embodiment.

Attention is first directed to Figs. 1 and 5 which show a tube 15 prior to being subjected to the work operations 70 performed by the first embodiment of the present invention. The tube 15, before being operated upon, is in the form of a smooth curvilinear section or elbow of

rectangular tubing which has been bent in the plane of its smaller dimension.

Fig. 1 also shows the first embodiment of a tube forming and dimpling apparatus in an assembled position prior to the actuation of the apparatus. The numeral 16 designates a base having mounted thereon a die block designated generally by the numeral 17, said die block comprising stationary die sections 18, 19, 21 and 22, which are rigidly secured to the base 16 by suitable means such as bolts 23. The stationary die sections 18, 19, 21 and 22 define a generally angular die cavity 24 for the reception therein of the tube 15 to be formed. The stationary die sections 18, 19, 21 and 22 further define passageways 27. The stationary die sections 18, 19, 21 and 22 are provided with apertures or grooves 28 and stationary die sections 18 and 19 are further provided with threaded apertures 29.

A forming and dimpling die 31 comprises a movable die section and is provided with a plane forming face 32 and convex dimpling projections or punches 33 and 34 extending from the face 32. The movable die section 31 is reciprocably mounted upon the base 16 in slideable relationship with the stationary die sections 18 and 19 and forms, in an actuated position, a portion of the wall of the die cavity 24 for engagement with the right-hand wall (Fig. 1) of the tube 15 to be worked upon. The movable die section 31 is attached by a shaft 36 to suitable actuating means such as a hydraulically operated piston (not shown).

An operating head 37 having a convex forming die 38 rigidly secured thereto is reciprocably mounted upon the base 16 in a slideway 39 and is connected by a rod 41 to an actuating means such as a hydraulically operated piston and cylinder 42. The convex forming die 38 is in slideable relationship with the stationary die sections 21 and 22 and is provided with plane forming surfaces 43, 44 and 46 for engagement with the left-hand wall (Fig. 1) of the tube 15 to be worked upon.

The interior of the tube 15 is supported during the forming operation by a sectional mandrel consisting of mandrel sections 47, 48, 49 and 51 (Fig. 6), said mandrel sections having, in an assembled position a configuration substantially the same as the finally desired shape of the tube.

Mandrel section 47, having substantially the same configuration as a straight portion of the tube 15, is slideably insertable into one extremity of the tube and has on one extremity thereof a projecting tongue 52 and on the other extremity thereof a shoulder 53 for engagement with the stationary die section 21.

The other extremity of the tube 15 is filled with mandrel sections 47, 49 and 51. Mandrel section 48 is provided with an inclined plane surface 54 for supporting the interior of the left-hand wall of the tube opposite the plane forming surface 46 of the convex forming die 38 and with a groove 56 for engagement with the tongue 52 on the mandrel section 47. Mandrel section 48 is also provided with a concavity 57 complementary in configuration to the convex projection 33 and opposed to the projection 33 when the mandrel sections are assembled within the tube. Mandrel section 48 is further provided with a shoulder 58 for engagement with the stationary die section 22.

Mandrel section 49 is provided with an inclined plane surface 59 for supporting one portion of the interior of the right-hand wall of the tube opposite a portion of the plane forming surface 32 on the movable die section 31. Mandrel section 49 is also provided with a concavity 61 similar to the concavity 57 on the mandrel section 48 and located opposite to the projection 34 when the mandrel sections are assembled within the tube. Mandrel section 49 is further provided with an inclined cam surface 60 and with a shoulder 62 for engagement with the stationary die section 18.

Another mandrel section, denoted generally by the

numeral 51, consists of a tapered or wedge-like portion 63 for insertion between mandrel sections 48 and 49 and a rectangular portion 64 for abutment with the shoulders 58 and 62 on the mandrel sections 48 and 49, respectively. The tapered portion 63 of the mandrel section 51 is provided with a plane inclined surface 66 for supporting another portion of the interior of the right-hand wall of the tube opposite a portion of the plane forming surface 32 of the movable die section 31. The rectangular portion 64 is provided with an aperture 67 for reception therein of a suitable tool to aid in the disassembly of the mandrel sections 48, 49 and 51.

Mandrel sections 47, 48, 49 and 51 are provided with slots 68 which are alignable in the assembled positions of the mandrel sections with the grooves 28 in the stationary die sections 18, 19, 21 and 22. The mandrel sections are retained in their assembled positions by means of slide members 69 which are slidably insertable into the grooves 28 and into the aligned slots 68.

In Fig. 3 is shown a top plate 71 adapted to be mounted upon the die block 17 in order to hold the positioned tube 15 in position during the forming operation. The top plate 71 is provided with apertures 72 alignable with the apertures 29 in the stationary die sections 18 and 19 and through which suitable connecting or clamping means (not shown) may be inserted. The top plate 71 is also provided with inserts or bosses 73 having polished surfaces raised above the surface of one side of the top plate. When the top plate 71 is clamped above the positioned tube 15 the inserts 73 contact portions of the tube 15 to hold the tube rigidly in position and to prevent scoring of the surface thereof. The top plate 71 is further provided with indentations 74 for engagement with a plurality of positioning blocks 76 which are secured to the stationary die sections 18 and 19 and which are adapted to accurately position the top plate 71 relative to the die block 17.

With the above described apparatus and tube in the assembled position the operating head 37 and the movable die section 31 are actuated into engagement with the left-hand and the right-hand walls, respectively, of the tube thereby effecting in a single step an angular forming of both the left-hand and the right-hand walls of the tube and a dimpling of the corners in the right-hand wall (Fig. 2) of the formed tube in the shape of concavo-convex dimples or corrugations.

Upon completion of the forming and dimpling operations, the top plate 71 is removed from the die block 17, the slides 69 are removed from the grooves 28, the mandrel section 47 is removed from the tube 15, and the tapered mandrel section 51 is then removed from the tube thereby allowing mandrel sections 48 and 49 to be removed from around the inwardly projecting dimples. The convex forming die 38 and the movable die section 31 are then retracted and the formed and dimpled tube may be removed from the die cavity 24.

Attention is next directed to Figs. 7 and 11 which show a tube 100 prior to being subjected to the work operations performed by a second embodiment of the present invention. The tube 100, before being operated upon, is in the form of a section of rectangular tubing which has been bent in a smooth curve in the plane of its larger dimension.

Fig. 7 also illustrates a second embodiment of a tube forming and dimpling apparatus in an assembled position prior to the actuation of the apparatus.

The numeral 81 designates a base. A die block is designated generally by the numeral 82 and comprises stationary die sections 83, 84, 86 and 87 which are rigidly secured to the base 81 by suitable means, such as bolts 88.

A forming and dimpling die 89 comprises a movable die section and is reciprocably mounted upon the base in slideable relationship with the stationary die sections 83 and 84 for engagement, in an actuated position, with the

right-hand wall (Fig. 7) of the positioned tube 100. The movable die section 89 is attached at one extremity thereof by means of a shaft 91 to suitable actuating means such as a hydraulically operated piston (not shown). The other extremity of the movable die section 89 is provided with a plane forming surface 92 and convex dimpling projections 93.

An operating head, designated generally by the numeral 94, is provided on one extremity thereof with a convex forming die 96 for engagement, in an actuated position, with the left-hand wall (Fig. 7) of the tube 100 to be worked upon. The operating head 94 is reciprocably mounted in a slideway 97 in the base 81 and is connected at the other extremity thereof by means of a rod 98 to suitable actuating means such as a hydraulically operated piston (not shown). Stationary die sections 83, 84, 86 and 87, together with the movable die section 89 and the convex forming die 96, define an angular die cavity 99 for supporting the external walls of the tube 100 to be formed.

The interior of the tube 100 is supported by two side-engaging compound mandrels designated generally by the numeral 101 and slidably mounted on the base 81 by means of retaining sleeves 105. The mandrels 101 comprise reciprocable arms 102, operating members 103, and arcuate cams 104. The reciprocable arms 102 are provided at first extremities thereof with T-shaped grooves 106 (Figs. 9 and 10) in which are movably mounted slideable sections 107. The reciprocable arms 102 and their corresponding slideable sections 107 are provided with arcuate surfaces 108 and 109, respectively, which, in the assembled position of the slideable sections 107 in the grooves 106, define concavities 111 complementary to the convex projections 93 on the movable die section 89.

The stationary die sections 83 and 84 are provided with threaded apertures 110 by means of which a top plate (not shown) may be attached to the die block 82, if desired, in order to restrain undue movement of the walls of the tube 100 during the forming operation.

In operation, a curvilinear section of tube 100 is placed in the angular die cavity 99 and the side-engaging mandrels 101 are partially inserted into the tube as shown in Fig. 7. The operating head 94 is then actuated to force the mandrels 101 into their final position within the tube as illustrated in Fig. 8, by acting upon the arms 103 in which position the convex forming die 96 engages the left-hand wall of the tube opposite to the arcuate cam members 104 to form an angular configuration in the left-hand wall of the tube as shown in Fig. 8.

A full understanding of the configuration and operation of the arcuate cams 104 may be obtained by reference to the aforementioned co-pending application wherein is disclosed an apparatus for producing seamless sharp bends in wave guide tubing, the second embodiment of the present invention being an improvement thereof.

Substantially simultaneously with the actuation of the operating head, the movable die section 89 is actuated into engagement with the right-hand wall of the tube whereby the right-hand wall of the tube is flattened between the reciprocable arms 102 and the plane forming surface 92 of the movable die section 89 and the corners of the right-hand wall of the angularly formed tube and are also dimpled in the shape of concavo-convex corrugations between the concavities 111 in the reciprocable arms 102 and the convex projections 93 on the movable die section 89.

Upon completion of the above-described work operations a suitable retracting force is applied to the free extremities of the mandrels 101 whereupon the inwardly projecting dimples in the tube bear upon the arcuate surfaces 108 of the slideable sections 107 to move the slideable

sections in the grooves 106 thereby allowing the mandrels 101 to be easily retracted from the tube.

It is to be understood that the illustrated embodiments are only illustrative of the present invention and that various modifications or additions may be made thereto without departing from the spirit and scope of the invention.

What is claimed is:

Apparatus for forming corrugations in prebent tubing which comprises a base having grooves formed therein, a plurality of stationary die sections rigidly secured to said base to form an angular die cavity for supporting the prebent tubing to be formed, a first mandrel slidably insertable within the angular die cavity and a first portion of the prebent tubing to be formed, the mandrel having a rectangular shoulder on a first extremity and an aperture near a second extremity, a sliding member received within a groove in the base and the aperture near the second extremity of the first mandrel for locking the first mandrel within the first portion of the prebent tubing, said first mandrel also having a concavity near its first extremity conforming in configuration and location to the corrugation desired to be formed in the prebent tubing, a second mandrel having a rectangular groove in a first extremity of sufficient size to receive the rectangular shoulder formed on the first mandrel and an aperture near a second extremity, the second mandrel slidably insertable within the die cavity and a second portion of the prebent tubing to be formed, a sliding member received within a groove in the base and the aperture near the second extremity of the second mandrel for locking the second mandrel within the second portion of the prebent tubing, said second mandrel also having a concavity near its first extremity conforming in configuration and location to the corrugation desired to be formed in the tubing, a first reciprocable forming die mounted on the base having a convex angular surface for angularly forming a first side of the prebent tube supported within said angular die cavity, a second reciprocable forming and corrugating die mounted on the base opposite said first reciprocable forming die, said second forming and corrugating die having a plurality of convex projections complementary in configuration and location to the concavities in the first and second mandrels so as to form corrugations in a second side of the prebent tubing opposite the first mentioned side of the prebent tubing when the second forming and corrugating die is advanced into the tubing, and means to reciprocate said first and second forming dies to simultaneously form and corrugate the prebent tubing.
